HIS ATTORNEYS

UNITED STATES PATENT OFFICE.

ALFRED M. LANE, OF ST. LOUIS, MISSOURI, ASSIGNOR TO MONARCH METAL PRODUCTS COMPANY, OF ST. LOUIS, MISSOURI, A CORPORATION OF MISSOURI.

WINDOW ATTACHMENT.

Application filed March 5, 1925. Serial No. 13,141.

To all whom it may concern:

Be it known that I, ALFRED M. LANE, a citizen of the United States, and a resident of the city of St. Louis and State of Missouri, have invented a new and useful Improvement in Window Attachments, of which the following is a specification.

This invention relates to window attachments particularly adapted for use in moving articles or materials into and out of buildings through the window openings therein. The principal object of the present invention is to devise a hoisting device which can be readily attached to and detached from a window without damage thereto and which, when in position, is capable of supporting a considerable load. Another object is to provide adjustments whereby the device may be attached to windows of different sizes and types. Other objects are simplicity of construction, reduced cost of manufacture, and compactness of design. The invention consists in the combinations and arrangements of parts hereinafter described and claimed.

In the accompanying drawing, which forms part of this specification and wherein like symbols refer to like parts wherever they occur.

Fig. 1 is a fragmentary face view of the inner face of the jamb member of a window frame in the region of the sash pulleys, showing a hoisting device embodying my invention attached thereto:

Fig. 2 is a vertical section on the line 2—2 in Fig. 1;

Fig. 3 is a horizontal section on the line 3—3 in Fig. 1; and

Fig. 4 is a vertical section on the line 4—4 in Fig. 1.

In the accompanying drawing, my invention is illustrated as applied to a double-hung window, whose sashes, parting strip and inside stop have been removed. In said drawing, 4 indicates the jamb or pulley-stile and 5 indicates a pair of sash-pulleys mounted in openings provided therefor in the pulley-stile and adapted to receive the weighted sash-lines (not shown) which slidably support the upper and lower sashes (not shown). This type of window con-

struction is well known and it is considered unnecessary to illustrate it in detail.

My hoisting device comprises a metallic bar or beam 10 adapted to be placed horizontally within the window frame adjacent to one of the pulley-stiles 4 in a position crosswise thereof. The bar 10 is located opposite the lower portions of the sash-pulleys 5 and extends beyond the inner and outer edges of the window frame. The bar is provided with a pair of parallel supporting rods 11 which project horizontally from one side of said bar. The supporting rods have straight inner end portions that are slidably mounted in transverse openings in the bar 10 and are threaded to receive nuts 12 that bear against the opposite sides of the bar and thus serve to lock said rods thereto in the desired adjusted position. The rods 11 are provided with upwardly curved free end portions 13 whose radius of curvature corresponds substantially to the curvature of the grooves in the sash-pulleys.

The beam 10 is attached to the window by inserting the rods 11 into the openings located beneath one pair of sash-pulleys 5 with their curved end portions disposed in the grooves of said pulleys and hooked around the rear portions thereof. By this arrangement, the rods 11 rest on the lower edges of the openings in which the pulleys are mounted and thus serve to support the beam, while the engagement of the curved end portions of the rods with the lower rear portions of the pulleys serves to prevent lateral movement of the beam away from the pulley-stile and resists any tendency for the free ends of the rods to swing upwardly and thus cause transverse tilting of the bar. One of the supporting rods is mounted in an elongated horizontal slot 14 in the hanger bar, whereby said supporting rod is adapted to be adjusted lengthwise of said bar to accommodate windows having sash-pulleys that are spaced different distances apart.

Slidably mounted on the inner end of the beam 10 is a sleeve 15 formed at its inner end with a lateral extension or flange 16 adapted to abut against the inner corner of the window stile. As shown in the drawing, the abutment flange 16 of the sleeve or

slide 15 is preferably provided with a pad of leather 17 which serves to prevent damage to the window casing when forced thereagainst.

- 5 The upper edge of the inner end portion of the beam is formed with teeth 18 which cooperate with corresponding teeth 19 formed in the upper surface of the opening that extends through the slide 15. This 10 opening has a greater vertical dimension than the vertical dimension of the bar, whereby the slide may be moved upwardly a distance sufficient to cause the teeth of the slide and the bar to become disengaged.
- 15 The co-operative teeth of the bar and slide are shaped like those of a saw and are arranged so as to resist movement of the slide away from the window while permitting the slide to be slid into engagement therewith. The adjustable slide 14 is provided 20 in its bottom with an upwardly bowed leaf spring 20 which bears against the under side of the hanger bar and thereby tends to hold the teeth of the bar and the adjustable 25 slide in engagement with each other. The slide, when forced against the window frame, serves to prevent vertical tilting movement of the bar; and it also prevents outward sliding movement thereof.
- 30 The outer portion of the hanger bar has a sliding fit in the upwardly diverging branches of a knee-brace 21 whose inner vertical leg is provided with an angle flange portion 22 adapted to fit the outside corner 35 of the window frame. The upwardly and outwardly inclined leg of the knee-brace is provided with a set-screw 23 which serves to prevent sliding movement of the hanger bar with relation to the knee-brace. It is 40 noted that the knee-brace performs the function of an inclined strut to brace and stiffen the overhanging portion of the beam and, at the same time, is adjustable longitudinally of the bar to accommodate window frames 45 of different thicknesses. The articles or materials that are to be hoisted or lowered are suspended from the outer end of the beam by a rope (not shown) that passes through a block 24 having a swivel connection 23 with a supporting hook 25 adapted to 50 be mounted in any one of a series of holes 26 provided therefor in the outer end of the beam.
- 55 It is obvious from the foregoing description that my hoisting device is very simple in construction, that it can be readily attached to and detached from a window, that it is capable of supporting a considerable load, and that it can be adjusted to fit windows of different sizes and types.
- 60 Obviously, the construction hereinbefore described admits of considerable modification without departing from the invention.

What I claim is:

- 65 1. A hoisting device adapted to be used

in a window frame provided with a sash pulley opening, said device comprising a beam adapted to be positioned within said window frame and members on said beam adapted to engage the inner and outer faces 70 of said window frame, said beam being provided with a lateral projecting portion adapted to engage the sash pulley opening of said window frame.

2. A hoisting device adapted to be used in 75 a window frame provided with openings having sash pulleys journaled therein, said device comprising a beam adapted to be positioned within said window frame and members on said beam adapted to engage the inner and outer faces of said window frame, said beam being provided with a laterally projecting portion adapted to enter said sash pulley opening and engage the pulley 85 therein.

3. A hoisting device adapted to be used in a window frame provided with openings having sash pulleys therein, said device comprising a beam adapted to be positioned within said frame and members on said beam adapted to engage the inner and outer faces of said window frame, and supporting members secured to said beam and projecting horizontally from one side thereof, said supporting members being adapted to be inserted 95 in said pulley openings beneath the pulleys therein.

4. A hoisting device adapted to be used in a window frame provided with openings having sash pulleys journaled therein, said 100 device comprising a beam adapted to extend through said window frame and members slidable on said bar and adapted to abut against the inner and outer faces of said window, one of said members and a portion 105 of the beam engaged thereby being formed with cooperating teeth, means for yieldably holding said teeth in engagement with each other, and supporting members secured to said beam and projecting horizontally therefrom, said supporting members being adapted to be inserted in the pulley openings beneath the pulleys therein.

5. A hoisting device adapted to be used in a window frame provided with openings having sash pulleys journaled therein, said device comprising a beam adapted to extend through said window frame and members adjustably mounted on said beam and adapted 115 to engage the inner and outer faces of said window frame, supporting members secured to said beam and projecting horizontally therefrom, said supporting members being adapted to be inserted in said pulley openings beneath the pulleys therein, and means 120 for adjusting said supporting members transversely of said beam.

6. A hoisting device adapted to be used in a window frame provided with openings having sash pulleys journaled therein, said 130

device comprising a beam adapted to extend through said window and members sleeved on said beam and adapted to abut against the inner and outer faces of said window frame, supporting members secured to said beam and extending transversely thereof, said supporting members being adapted to be inserted in said pulley openings beneath the pulleys therein and having upwardly curved free end portions adapted to engage 10 said pulleys, and means for adjusting one of said supporting members longitudinally and transversely of said beam.

Signed at St. Louis, Missouri, this 24th day of February, 1925.

ALFRED M. LANE.
